AUTOMATIC FACSIMILE MESSAGE
SCANNING SYSTEMCharles N. Gillespie, Brooklyn, N. Y., assignor to
Radio Corporation of America, a corporation
of Delaware

Application April 24, 1943, Serial No. 484,383

10 Claims. (Cl. 178—6.6)

1

The present invention relates to facsimile transmitting and receiving equipment, and more particularly to automatic apparatus for feeding, scanning and discharging subject or record sheets in a novel manner.

The term "sheets" is used to designate either message sheets provided with subject matter for transmission, or recording blanks of any kind. The term "scanner" will be used to designate a device for generating intelligence signals or a similar or different device provided with suitable instrumentalities for marking a surface in accordance with received signals.

In facsimile scanners of the prior art arranged to scan a series of subjects for transmission or reception, it is necessary to employ a continuous web having the different messages inscribed thereon for transmission, or a strip or web of recording paper or film, these webs being fed continuously over the active portion of the scanner at a constant rate of speed, or in some instances at a speed which is higher than at scanning speed between the pieces of scanned subject matter whether the scanning operation is performed for the purpose of transmitting or recording picture signals. Automatic operation of scanners adapted to receive and scan discrete pieces of subject matter, such as message sheets or separated recording blanks, has been possible only by securing the separate sheets or blanks in some manner to a web or belt which is moved intermittently or continuously. Where the message sheets or blanks move with the belt through the scanning zone, it is necessary to detach them individually from the belt after the completion of a scanning operation. Where the sheets or blanks are received from a web or belt and held by a movable or stationary part of the scanner during scanning, it is also necessary to remove the sheets or blanks by performing a separate operation.

Moreover, in prior art attempts to save transmission time of the recording channel which is used for facsimile communication, it has been necessary to change the speed of a movable element of the scanner or to interrupt the scanning operation at a time depending on the area of the sheet to be scanned for transmission. If the recording scanner working in conjunction with a transmitter employs separate blanks, the recording operation at the receiver must be interrupted concurrently with the interruption of the scanning operation at the transmitter. These prior art arrangements reviewed briefly above require

2

complicated electrical or mechanical control and timing systems.

Feeding and scanning separate sheets in a novel manner, which eliminates the necessity for webs and belts serving as holders or conveyors and, also, eliminates the necessity for control and timing systems, is an important object of the present invention.

In accordance with the present invention it is unnecessary to use message sheets or record blanks having anything on or in the blanks to control operation of the scanner. The sheets may be of the size desirable for business or other reasons, but the area presented to the scanner is controlled in a novel manner. The manner of obtaining this control is also an important object of the invention.

In accordance with the invention the subject or record sheets are fed to the scanner in an overlapped manner, the degree of overlap being predetermined for a series of sheets or from sheet to sheet, if desired, by employing suitable signals from the transmitter. Where the recorder in a facsimile system is to be operated in a like manner, a simple auxiliary signal may be sent from the transmitter to the receiver to indicate the amount of overlap which is to be obtained in the recorder. Subject and record sheets may be of different sizes if desired, the novel sheet feeding arrangement for the accompanying scanner being set to compensate for the difference in size of sheet employed at the transmitter and recorder.

Also in accordance with the invention, a continuous flow of overlapped subject or record sheets is maintained which forms in effect a moving curtain which may be employed to cover the active portion of the scanner. When so employed, light is kept out of the scanner, which permits the exposed portion of the scanner to be made of glass or any other transparent substance without interference with the scanning process by external light. In a recording scanner the continuous flow of blanks may serve as a means for excluding external light so that photographic recording methods may be employed if the blanks are sufficiently opaque.

A further object of the invention is to provide a novel sheet feeding arrangement, the operation of which may be correlated with respect to the operation of an associated facsimile scanner.

Still another object of the invention is to provide a novel method of handling message sheets and recording blanks so as to provide a fast and effective record communication service available to patrons of the service.

Other and more specific objects of the invention will become apparent and suggest themselves to those skilled in the art to which the invention is directed upon reading the following specification and claims in connection with the drawings in which:

Fig. 1 is a perspective view of a scanner equipped with an automatic sheet feeding arrangement in accordance with the invention;

Fig. 2 is a fragmentary view of a detail of the machine of Fig. 1;

Fig. 3 is a sectional elevation taken on line 3—3 of Fig. 1;

Fig. 4 is a perspective view of a modification of Fig. 1;

Fig. 5 is a diagrammatic showing of a portion of a further modification of the machine of Fig. 1 illustrating essential features of a timed sheet feeding arrangement;

Fig. 6 is a continuation of Fig. 5 and is a diagrammatic showing of the scanning portion of the machine;

Fig. 7 is a fragmentary sectional elevation taken on line 7—7 of Fig. 6;

Fig. 8 shows message sheets of this invention and the manner of supplying them to the scanner;

Fig. 9 shows message sheets having subject matter occupying substantially the entire message bearing area of the sheet;

Fig. 10 is a fragmentary perspective view of a modification of this machine of Figs. 1 and 6; and

Fig. 11 is a fragmentary sectional elevation taken on line 11—11 of Fig. 10.

Referring to Fig. 1 of the drawings, reference character 10 is applied to the housing of the facsimile machine, including a scanner 11 shown as a transmitting scanner, but which may be operated as a recorder with certain changes in its mechanism, as is well known in the prior art. The scanner 11 is shown by way of example as being a radial optical type in which a central shaft 14 supports and drives a pair of oppositely disposed optical system tubes 16 and 17, which cooperate alternately with either a slot or transparent portion 19 of a sheet supporting element 21. In the illustrative embodiment, the sheet supporting element 21 is in the form of a curved top for the housing 10. If desired, the entire sheet supporting element 21 may be of transparent material such as glass or a transparent plastic. Sheet supporting element 21, the surface upon which the sheets are to slide, is smooth and preferably polished. Photographic recording may be obtained by substituting a source of message signal modulated light beam influencing a light sensitive film, or electro-chemical recording may be obtained in accordance with any one of the well known systems of the wet or dry recording type by mounting a stylus or several styluses upon the shaft 14. A scanner of the general type shown by Fig. 1 is disclosed in Patent No. 1,792,264, issued February 10, 1931, to E. F. W. Alexanderson. The output connection to the scanner 11 is indicated at 22 and it may be connected to any suitable communication channel, such as the illustrated radio transmitter 23 by way of an amplifier and some form of coding and keying equipment 24 which may be, for example, of the constant frequency variable dot type as the sub-carrier frequency modulated types which have each been explained in published literature. Reference character 25 indicates a radio receiver connected to a facsimile recorder

26 which may have a scanner similar to the scanner 11 modified as suggested by employing recording styluses or light modulation in the case of photographic recording. The general recorder 26 may, if desired, be in other respects similar to that shown in Fig. 1 of the drawings including the record sheet feeding arrangement or it may be of any other desired type. While a radio communication link is indicated between the transmitter 23 and the receiver 25, it will be understood any type of communication channel such as a land line between a local message collecting point and a central office may be employed.

15 A side 27 of the housing 10 is shown as providing a support for the sheet propelling means to be described. Message sheets or blanks are propelled over the surface 21 by an endless belt 28, the linear speed of which is correlated with the speed of rotation of the scanner 11 in the usual manner so that light from the tubes 16 and 17 of the optical systems traverses the sheet in closely spaced lines.

20 A suggested means of obtaining the correlated operation of the belt 28 with the shaft 14 may comprise a motor 31 of either the synchronous or speed controlled type, which drives the shaft 14 through a gear and pinion combination 33. The motor 31 also drives a shaft 36, which is supported in suitable bearings 37 housed in brackets 38 secured to the side 27 of the casing 10. Pulley shafts 41 and 42 are driven by worm and worm wheel combinations 44 and 46 respectively. The shafts 41 and 42 may be rotatably carried by 25 bearings housed in bearing brackets 49 and 51. It will be understood that these brackets 49 and 51 are duplicated on the side of the machine opposite the side 27. A pulley 52 is mounted on the shaft 41, and a corresponding pulley 53 is mounted on the shaft 42. Similar pulleys 54 and 55 (Fig. 2) are provided adjacent to the opposite edge of the belt 28 and are supported and driven by shafts 56 and 57 corresponding to the shafts 41 and 42.

30 Fig. 2 of the drawings shows the arrangement for supporting and driving the pulleys between the end pulleys 52 and 54 and the end pulleys 53 and 55. Transverse members 58 are secured at each end 59 to the side walls of the casing 10. A supporting arm 61 extends longitudinally of the casing 10 and provides a bearing support for the shaft 41. A similar supporting arm 62 provides a bearing support for a shaft 63 upon which is secured a pulley 64. The shaft 56 for 35 the pulley 54 is journaled in a third shaft supporting arm 67. The supporting arms are duplicated to provide bearing supports for the shafts 42, 57 and a shaft 68 for a pulley 69. The shaft 63, displaced radially from the shafts 41 and 56, is connected to these shafts through universal joint connections 69 and 71 and intermediate drive shafts 72 and 73. It will be noted that the universal joint connections 69 as well as the connections 71 are angularly displaced with respect to each other so that the shafts turn with substantially uniform angular velocity. The pulley 69, displaced radially from the shafts 42 and 57 in a manner similar to the displacement of the pulley 64, prevents lateral shifting of the belt 28 and also maintains it in close contact with surface 21 of the housing 10.

35 Message sheets or recording blanks assembled in a pile are placed in a box 82, which is rectangular in outline and of dimensions suitable to prevent material displacement of the sheets in

the pile. A slot 83 is provided in the wall of the box 82 through which the blanks are projected one at a time so as to be caught under the belt and propelled along the sheet supporting element 21 of the housing 10 at the desired scanning speed.

Feeding of the blanks one at a time is accomplished in the embodiment of Fig. 1 by means of spaced rollers 84, the peripheries of which project through slots 86 in the bottom of the box 82. The peripheral surfaces of the rollers are provided with suitable friction material. The rollers 84 may be, and are preferably carried by universal joint connected shafts or a flexible shaft journalled in a support (not shown) movable with respect to the bottom of the box so that the amount which the rollers project through the slots 86 may be adjusted. Three of the rollers 84 are shown illustratively, but it will be understood that this number may be varied within the scope of the invention.

The box 82 may, if desired, comprise four upstanding walls, the bottom being formed by the surface 21 or an extension thereof, or it may be a separate detachable receptacle which may be preloaded with sheets. A plurality of boxes may be provided for preloading.

A weight 88 is shown as resting on the pile of sheets to keep the bottom sheet of the pile in frictional engagement with the rollers 84. As a matter of convenience, the weight 88 may be pivotally connected to links 91, which are in turn pivoted to a hand lever 92 which is swingably mounted on a wall of the box 82.

The driving connection 94, which imparts movement in unison to all of the rollers 84, for example, in the same manner as the pulleys 52, 64, and 54, are driven, is connected as shown by way of example in Fig. 1 to a worm and worm wheel combination 96. As a possible alternative the shaft 94 may be connected through a suitable speed reducing gearing to the scanner drive shaft 14.

In operation of the machine of Figs. 1 to 3 as a transmitter, for example, a plurality of previously inscribed stacked message sheets are placed in the box 82 and when the machine is set in operation the bottom sheet will be projected through the slot 83 until it is gripped between the belt 28 and the top 21 of the casing 10. After the first sheet has been withdrawn sufficiently to permit the rollers 84 to contact the next sheet, the next sheet in turn will be projected between the top 21 of the casing 10 and the belt 28. The sheets can be fed to the belt in overlapped relationship so that the portion of the following sheet, which is inscribed with a message, will cover up printed headings of the preceding sheet, thus preventing time being wasted by scanning the heading. The amount of overlap is controlled in the machine of Fig. 1 by the position of the rollers 84 with respect to the slot 83 and the adjacent bight of the belt 28.

The motor 31 as shown is provided with a speed control 98 so that the speed of scanning may be increased if desired. An arrangement which is possible, inasmuch as the drive for the belt 28, the drive for the shaft 14 and the rollers 84 are all correlated. The suggested speed control for the motor 31 is useful only where synchronization of the transmitter and recorder is maintained in some other manner than the frequency of the main motor supply. For example, a small A. C. generator may be mounted on the shaft

36 at the transmitter to generate synchronizing voltages.

The sheets are ejected in succession from the end of the machine after they have been completely scanned without any need for special handling or conveying devices.

Operation of the machine as a recorder proceeds in the manner already described, except that the sheets placed in the box 82 are message blanks of some suitable type which will be operated upon by styluses, or other marking devices, carried by the shaft 14. These blanks may also be provided with printed headings corresponding with the headings on the message sheets at the transmitter. If the headings on both the message sheets at the transmitter and the message blanks at the recorder are of the same extent, the rollers 84 in the transmitter and recorder will be located in the same relative position with respect to the slot 83 and the active bight of the belt 28.

As pointed out above, if opaque blanks are used having a light sensitive surface, these blanks may be assembled in a pile in a closed box 82 and fed over the surface 21 of the housing 10 with their ends overlapped which will exclude light from the interior of the housing 10 so that the blanks will be exposed only to intelligence modulated light emitted from a scanner carried by the shaft 14. With this arrangement it will be necessary to process the blanks and this may be accomplished by providing an extension of the machine casing top 21 having a suitable cover under which the blanks may be carried by an arrangement similar to the rollers 84. Photographic processing may be carried out under this cover or the blanks may be passed from under the cover to a light tight processing box.

If the blanks are of a type which must be conditioned in some manner, as by moistening before the recording step is performed, this is preferably done after the blanks emerge from the slot 83 and before they are seized by the belt 28. The reason for this procedure being that the blanks may be more easily handled if they are substantially moisture free or contain the normal amount of moisture present in all paper products under more or less normal atmospheric conditions.

Fig. 4 of the drawings shows a modification of the machine of Fig. 1 in which the message sheets or blanks lie flat in a box or receptacle 102, which corresponds to the box 82 shown in Fig. 1. The scanning equipment (not shown) may be housed in the casing 104 of the machine which is provided with a curved top 106 similar to the top 21 of the casing 10. Scanning is accomplished by passing message blanks or record sheets over a slot 107 in the top 106. The sheets are propelled by a roller 108 and rollers 109 and 110. These rollers are driven by mechanism (not shown) which may, for example, be similar to the drive for the pulleys of Fig. 1 at equal peripheral speeds at the point of contact with the sheets or blanks.

The sheets or blanks, piled in the box 102, are projected one at a time through a slot 112 by means of rollers 114 which project upwardly through slots 116 in the bottom of the box 102.

A hood member 118 serves to curve each sheet to lie closely to the top 106 of the casing so that it attains the proper curved configuration as it passes over the scanning slot 107. A series of rollers 119, two in number in the illustrative example of Fig. 4, may be, and preferably are, driven along with the roller 108 and the rollers

109 and 110 so that their peripheral speed at the point of contact with a sheet or blank is the same.

As the sheets are projected one at a time from the box 102 they are received and guided by the rollers 119 and passed under the hood 118. The sheet or blank is then passed over the scanning slot 107 and into a receptacle 122.

Figs. 5 to 7 of the drawings show a modification of the invention in which a different type of feed device is used for introducing sheets one at a time to the scanner. An arrangement, by way of example, is also disclosed whereby the degree of overlap may be adjusted at will. The general organization of the illustrative example is somewhat the same as that shown in Figs. 1 and 4 of the drawings for the sake of ease of illustration and description. However, it will be understood that equipment embodying the invention may be made in numerous forms, for example, the scanner may be of the "flat bed" type with a light tube or stylus traversing the sheet from side to side, or with a scanner of the helical type cooperating with the sheet.

The scanner equipment shown schematically on Fig. 6 of the drawings is indicated generally by reference character 126 and comprises optical scanning tubes 128 cooperating with a slot 131 in the cover 132 of the scanner. A plurality of belts 133, 134, 135 and 136 passing over forward pulleys 137 and rear pulleys 138, which pulleys may be supported and driven in the manner described in connection with Fig. 1 of the drawings, serves to propel message sheets or blanks over the curved top 132. A fifth belt, corresponding to the belt 133, located on the opposite side of top 132, is not visible on Fig. 6. The belt 135 is in the middle of the top 132. While five belts have been indicated, a single belt such as the belt 28 of Fig. 1 may be provided, however, such an arrangement is not preferred. A sufficient number of belts preferably is provided, as shown in Fig. 10 and 11 briefly described hereinafter, so that the top 132 is substantially completely covered. The effectiveness of the sheet propelling belts may be enhanced by providing an additional belt 140 which contacts the underside of a message sheet or blank through a slot provided for this purpose in the top 132. A plurality of belts 140 may be provided. The belts 133 to 136 and the belt or belts 140, if they are employed, may be driven in the manner shown by way of example in Fig. 1 of the drawings, or by flexible shafts except that the pulleys will be axially aligned.

The sheet feeding arrangement, schematically shown in Fig. 5 of the drawings, comprises a box or basket 143 for holding a pile of message sheets or recording blanks, depending on whether the machine is to be used as a transmitter or a recorder. An opening 144 extending laterally of the box 143 near its end adjacent the scanner 126 provides for withdrawal of the blanks one at a time from the box by a vacuum operated pick-up bar 146 which may be constructed of a hollow rectangular bar with a perforated top 147 as shown. A flexible conduit 148 connects the interior of the device 146 with a vacuum pump 149 or an air exhausted reservoir by way of a valve 150, the function of which will be later described.

The bar 146 is arranged to move downwardly as shown by the dotted arrow 151 and forwardly as shown by the dotted arrow 152, which movements may, for example, be accomplished by the system of levers and cams shown on the drawings. The bar 146 is mounted on the end of an arm 153 which normally pivots around a fixed

axis 154 and is held in the position shown by a tension spring 155. The arm 153 is free to move horizontally against the retractile force of the spring 155 by means of a slot 156. A lever 157 is hinged to the arm 153 and also to a lever 158 by pivot pins 161 and 162 and is free to rotate about these pins in the plane of the drawing. The lever 158 is swingably journaled on a fixed axis 164. A series of cams 166, 167 and 168 are mounted on the same shaft or are made to move in correct angular relationship by an equivalent means. The angular relationships or phase positions of these cams are shown by Fig. 5. Cam 166 moves the lever 158 downwardly as shown on the drawing by a cam follower 171 against the retractile force of a tension spring 172, one end of which is fixed and the other end of which is connected to the end of the bar 156, thus moving the vacuum bar 146 downwardly by the desired amount indicated by the dotted arrow 151 referred to above. While the lever 158 is held in its dotted line position by the cam 166, the cam 167 operates the arm 157 through the agency of a reciprocal follower 173 to the right as shown on the drawing, thus moving the bar 153 and the vacuum bar 146 to the left against the retractile force of the spring 155. The dotted arrow 152 indicates substantially the direction and amount of this movement. When the cam 167 has operated the vacuum bar 146 to the limit of its horizontal movement, the cam 168 closes the valve 150 and opens a passage 174 communicating with the atmosphere, allowing air to fill the flexible conduit 148 between the vacuum bar 146 and the valve 150, thus releasing a message blank or sheet previously picked up by the vacuum bar in a manner to be described in connection with a description of the operation of the equipment. Following release of the message blank or sheet, the cam 167 permits the vacuum bar 146 to be moved to the right by the tension spring 155. After completion of this motion, the cam 166 permits bar 146 to be moved upwardly by spring 172. Then the cam 168 again places the conduit 148 in communication with the vacuum pump 149, and the vacuum bar 146 is then ready to execute another sheet extracting cycle.

A message sheet released by the vacuum bar 146 is seized between a pair of rollers 177 and 178 (Figs. 5 and 6). Movement of the free end of the sheet or blank between the rollers 177 and 178 is facilitated by a pair of curved guide plates 181 and 182 which converge so as to provide a narrow opening adjacent the line of contact of the rollers 177 and 178. Contacting belts 183 and 184 pass over the rollers 177 and 178 respectively and also over pulleys 186 and 188. The point of emergence of an advancing sheet from between the belts 183 and 184 coincides with the top 132 of the scanner 126. The line of contact between the rollers 177 and 182 and the line of contact between the belts 183 and 184 at the pulleys 186 and 188 preferably lie in the plane of the bottom run of the belt 135 between pulleys 137 and 138. The belt 135 is located substantially in the center of the scanner top. The advancing end of the message blank curves by its own weight so that it will be received between the top 132 of the scanner and the belts 133 to 136. Curved sheet guides 191 and 192 insure this curvature of the end of advancing sheet. Another guide 193, which is substantially a continuation of the top 132, is mounted beneath the guides 191 and 192. The advancing sheet passes

between the guides 191 and 192, and the guide 193.

Two successive message blanks or sheets 194 and 195 are shown in Fig. 5 as having been fed to the sheet receiving rollers 177 and 178. Figs. 8 and 9 of the drawings also illustrate the relative position of two successive sheets in the relative position in which they pass through the scanner and will be referred to more in detail hereinafter in connection with the description of the operation of the automatic message feed and scanner. The amount of overlap of successive sheets in the illustrative embodiment of Fig. 5 of the drawings will depend upon how rapidly the vacuum bar 146 is moved, or how soon the next blank in a series of blanks is fed to the rollers 177 and 178. The sooner the next succeeding blank is presented, the greater the overlap. The amount of overlap may be controlled by varying the speed of the shaft or other drive means for the cams 166, 167, and 168. Fig. 5 of the drawings indicates illustratively a drive means 196 to be described for accomplishing this purpose.

A motor 198, preferably of the synchronous or speed controlled type, which may also drive the scanner 126, by any well known power transmission means (not shown), imparts driving power through a suitable gear and pinion combination 201 to the speed control mechanism 196. The motor 198, as shown on Fig. 6 of the drawings, may conveniently operate the rollers 177 and 178 through gearing 199. Where the scanner 126 is also driven from the motor 198, as suggested above, the series of belts 133 to 136 and the belt or belts 140 will also derive power from the motor 198. The common drive arrangement suggested will provide the operation for the sheet feeding means and scanner in synchronism. However, it will be understood that separate driving motors may be used for the speed control mechanism 196, the feed rollers 177 and 178 and the scanner 126, synchronism being maintained by any known means.

The motor 198 is preferably of the synchronous or speed control type so that the scanner, if it is driven from this motor, as suggested above, will operate in synchronization with the scanner at the transmitter. If the variable speed motor is employed, any of the synchronizing methods which are now well known in the art may be employed to insure synchronous operation of the scanner 126 with the distant scanner. If the arrangements above (Figs. 5 and 6) are employed as a recorder, the distant scanner will then normally be the source of synchronizing signals or impulses.

The speed control mechanism 196 comprises a friction cone 202 mounted on a shaft 203 driven by the gearing 201. A second cone 205 cooperating with the friction cone 202 through a friction roller 208 is mounted on a shaft 209. As indicated diagrammatically on Fig. 5 of the drawings the shaft 209 supports and drives the cam group comprising the cams 166 to 168. It will be understood, however, that these cams may be mounted on separate shafts, if desired, interconnected by a suitable gearing and that any suitable speed regulating device may be substituted for the friction cone arrangement shown by way of example. The friction roller 208 is slidably mounted on a rod 212 and is moved for speed control purposes by a forked arm 216, the end of which is in threaded engagement with a screw shaft 217. The latter is provided with a hand crank 218 so that the axial position of the friction

roller 208 may be adjusted thereby regulating the speed of rotation of the cams.

Operation of the equipment shown in Figs. 5 and 6 as a message transmitter will now be described. However, it is to be understood that this equipment may be operated as a recorder in the manner pointed out above in connection with Figs. 1, 2 and 3 of the drawings. The message sheets, which have been prepared for transmission by having each patron of the message communication service inscribe a message thereon, or by the typing of a message by an attendant or operator are arranged in a pile in the box 143 as shown with the top of each sheet adjacent the edge of the box most remote from the scanner 126.

Referring to Figs. 8 and 9 of the drawings, two successive message sheets 194 and 195, bearing short messages, are shown in the relative position that they occupy with respect to each other as they pass through the scanner 126. Fig. 9 shows two successive message sheets 224 and 225 bearing messages of maximum length in their relative positions occupied in passing through the scanner 126. These long messages in general will be press matter or other dispatches which may be conveniently typed or inscribed on a series of message sheets. The message sheets of Figs. 8 and 9 will have a portion of their surface area devoted to printed headings indicated by the reference character 227, and as shown in Fig. 8 this heading, will in normal operation of the scanner, be covered by the next successive blank to be scanned so that communication channel time will not be wasted by scanning this heading at the transmitter and an equivalent area of the blank in the recorder. Message sheets adapted to cooperate with a message feed device embodying the invention may, if desired, be provided with a dotted line 229. A printed suggestion that a patron of the service write the message below this line, if the message to be transmitted is short, for example, within the ten word limit set by the cost of the service, may appear on the sheet. The line 229 and explanatory printed matter, if it is used, may be printed or otherwise inscribed in a colored ink or dye to which the optical or other scanner of the transmitter is relatively insensitive. By employing message sheets just described as forming a part of this invention, several advantages accrue which have been pointed out, and others will appear as the description of the operation of the invention proceeds.

The message sheets are removed one at a time from the box 143 in the manner fully explained above by the timed operation of the vacuum bar 146. Each message sheet after it has been introduced between the rollers 177 and 178 is drawn forwardly while it remains flat for a short distance of travel. The trailing edge of the message sheet hangs down on the guide 182, where it is clear of the vacuum pick up bar 146 which will lay the leading edge of the next message sheet on top of it by an amount depending on the desired overlap. The desired degree of overlap will, as pointed out above, be obtained by adjusting the speed of rotation of the shaft 20 by turning the hand crank 218. The degree of overlap to be obtained will be determined as pointed out above by the length of the message inscribed on each sheet in the practice usual with record communication services for hire, numerous messages will be of "standard" short length because of the word number limitation set by the price of the service or the area of the blank to be scanned for transmission for a given fee. Therefore, these

11

short messages may readily be sorted or placed as they are inscribed in a box 143, since they will be in the majority. With a box 143 containing these short messages in position on the machine, the machine will be operated with an appropriate setting of the hand crank 218. Positioning of a message on a message sheet so that complete scanning of the message subject matter will be obtained is facilitated by the mark or line 229 described above. The full length messages, such as are indicated on message sheets 224 and 225 of Fig. 9, may also readily be sorted out and placed in a box 143 of another machine or a box which may replace a box already in use, or may be piled together and placed on top of the pile of short messages with an indicating sheet of distinctive color between the piles. When the indicating sheet is drawn from the pile, it will be an indication to the operator that the setting of the hand crank must be changed. Moreover, the color and/or matter printed on the indicating sheet may be used to apprise the operator of the speed setting of the speed regulating device 196 to be used.

As a blank progresses between the rollers 177 and 178 it is supported in the middle by the belts 183 and 184. As soon as the trailing edge of the blank leaves the rollers 177 and 178 the outer edges will fall, thus bending the blank approximately to the shape of a half cylinder as indicated at reference character 231 in Fig. 7 of the drawings. When this occurs, the leading edge of the sheet, for example the sheet 195 shown in Fig. 5 of the drawings, will engage the guide 191. The guide 193 which is substantially a continuation of the top 132 is mounted beneath the previously mentioned guide 191. The sheet 195 will then be pressed to the curved surface of the scanner 132 and pushed under the roller-belt combination 133, 136 and 138. Belts 183 and 184 are approximately the same size as belts 133, 135 and 136, and the plane between the touching runs of the belts 183 and 184 should approximately coincide with the plane between the touching surface of the centrally located belt 135 and the top of the scanner 139.

Once a sheet, for example a sheet 195, is engaged by belts 133 to 136 it moves over the scanning slot 131 in the manner described above in connection with Fig. 1 of the drawings.

After the sheets have passed over the scanning slot 131 they may be deposited one at a time in any suitable box or receptacle such as the receptacle 122 shown in Fig. 4 of the drawings, or if the machine of Figs. 5, 6 and 7 is being operated as a recorder the recorded sheets may be deposited in or on any suitable conveyor system for distribution to a delivery point or points.

Two similar machines embodying features disclosed by Figs. 5, 6 and 7 of the drawings may operate together as a transmitter and recorder over a suitable radio or other communication channel. Where this is done the subject matter sheets at the transmitter may differ in size from the message blanks used at the machine operating as a recorder. The sheet feeding speed controls on the transmitter and/or recorder may be used to compensate for this difference in size. The sheets used for either purpose, therefore, may be of any given height as measured from top to bottom and any desired portion of this height may be devoted to a printed heading or a characteristic marking used to designate the character of the sheet and its intended use. An auxiliary signal may be sent from the transmitter to the

12

recorder in any suitable manner to indicate to the operator at the recorder the degree of overlap which is to be obtained by varying the speed of operation of the sheet feeder.

Inasmuch as successive sheets fed to the scanner are placed on the scanner in a definite angular position with respect to a selectable angular position of the scanning head 128, no special problem will be presented in deriving and/or transmitting framing or phasing signals and no marks for this purpose need appear either on the message sheet or the message blank. Where the motor driving the scanning head at the transmitter is maintained in synchronism and phase relationship with the motor driving the scanner at the recorder no frequently repeated phasing signal will be required.

Referring to the previously mentioned modifications shown on Figs. 10 and 11 of the drawings, a support 231 is shown which corresponds to the support 58 in Fig. 1 of the drawings. A plurality of bearing brackets 232 is secured to the support 231 to provide bearing supports for the pulley shafts 233 of pulleys 236. These pulleys may be made of solid rubber and are preferably cylindrical. The individual shafts 233 are interconnected by universal joints located between the pulleys and a driving connection shown as a shaft 237 projects from the end-most pulley 236 and may be driven in the same manner, for example, as the shaft 41 shown in Fig. 1 of the drawings. The pulleys 236 support and drive a plurality of belts 238 which substantially cover the top 241 of the scanner housing.

The nature of the invention will be determined from the foregoing and the scope thereof is defined in the appended claims.

Having now described my invention, what I claim as new and desire to have protected by Letters Patent is:

1. Facsimile apparatus comprising a sheet support element, means to move sheets along said element, a scanning element cooperatively positioned relative to the support to scan a sheet supported thereon, and means for feeding a series of independent sheets in sequence and in overlapped relationship upon the support element to be moved by said first named means for scanning.
2. Facsimile apparatus comprising a record support element, a scanning element cooperatively positioned relative to the support to scan a record sheet supported thereon, means for feeding a series of independent record sheets in sequence and in overlapped relationship upon the support element for scanning, and means to vary the degree of overlap of said sheets.
3. In a facsimile system, a transmitter having scanning means for developing signals in accordance with subject matter to be transmitted, a recorder having a scanner capable of marking a recording medium in accordance with signals received from said transmitting scanner, means correlated with said transmitting scanner for feeding entirely separate pieces of subject matter thereto in overlapped relationship, said transmitting scanner having means to maintain the overlapped relationship of said separate pieces of subject matter and means for feeding a recording medium to said recording scanner.
4. In a facsimile machine, a scanner, means for providing operating power for said scanner, means to feed separate sheets successively to said scanner, and means for causing said sheet feeding means to feed each sheet of a series of successive

sheets in a manner to cause a sheet fed successively to overlap a sheet previously fed to said scanner, the overlapped portion being maintained out of cooperative relationship with said scanner.

5. In a facsimile machine, a scanning device, mechanism for placing entirely separate sheets into scanning relationship with said scanning device comprising, means to retain said sheets in readiness to be scanned, means to remove said sheets one at a time in succession from said sheet retaining means, means to bring a sheet removed from said sheet retaining means into scanning relationship with said scanning device, and means to provide for overlapping successive sheets as they come into scanning relationship with said scanning device.

6. A facsimile machine comprising a scanner having stationary supporting means for a sheet, means to traverse a sheet along closely spaced scanning lines of an image area to be scanned, means to impart movement to a sheet in said scanner to produce spacing of said scanning lines traced on the image area, sheet feeding means for introducing sheets successively, one at a time, to said movement imparting means, and means for correlating the speed of operation of said sheet traversing means and said movement imparting means.

7. A facsimile machine comprising a scanner having means to traverse a sheet along closely spaced scanning lines, means to impart movement to a sheet in said scanner to produce spacing of said scanning lines, sheet feeding means for introducing sheets successively, one at a time, to said movement imparting means, means for correlating the speed of operation of said sheet traversing means and said movement imparting means, and means for driving said sheet feeding means at any one of a plurality of different sheet introducing speeds with respect to the speed of said movement imparting means.

8. A facsimile machine comprising a scanner having a portion presenting a curved stationary surface over which a sheet is to move during a scanning operation, sheet propelling means comprising a moving web positioned so that a sheet to be scanned is received between said web and said stationary curved surface, means for feeding sheets, one at a time, successively to said web comprising a pair of moving webs positioned to receive a sheet between them, and guide means for curving a sheet carried by said pair of moving webs to conform to the curvature of said stationary surface.

9. In a facsimile system, a transmitter having a scanner, means for feeding sheets one at a time in succession and in overlapped relationship to said scanner, a recorder having a scanner, means for feeding sheets one at a time in succession and in overlapped relationship to said recording scanner, means at said transmitter for causing operation of said associated sheet feeding means at a predetermined speed, and means at said recording scanner for causing operation of its associated sheet feeding means at a speed of operation different from that of the sheet feeding means associated with said transmitter scanner, whereby sheets fed to said recording scanner to receive a facsimile record of matter appearing on the sheets scanned at the transmitter may differ in size and degree of overlap from the sheets fed to said transmitting scanner.

10. Facsimile apparatus comprising means to support a plurality of message sheets, a scanning element cooperatively positioned relative to said supporting means to scan one of said message sheets supported thereon, each message sheet comprising a portion having a fixed indicia appearing thereon, the remaining portion of said sheet being available for cooperation with said scanning element, a mark in a predetermined position on said subject matter receiving portion to one side of which a short piece of subject matter is to be inscribed, and means for feeding a series of said discrete and individual message sheets in sequence and in overlapped relationship to said supporting means for a scanning operation upon said available portion of each.
